UNITED STATES PATENT OFFICE.

LUDWIG RUCHSTEIN, OF NEW YORK, N. Y.

DESIGN FOR A TOY FIGURE.

SPECIFICATION forming part of Design No. 37,068, dated August 9, 1904.

Application filed June 6, 1904. Serial No. 211,409. Term of patent 7 years.

To all whom it may concern:

Be it known that I, LUDWIG RUCHSTEIN, a citizen of the Empire of Austria-Hungary, residing in New York, borough of Manhattan, in the State of New York, have invented a new, original, and ornamental Design for Toy Figures, of which the following is a specification, reference being had to the accompanying drawing, forming a part thereof.

10 The figure is a side elevation of a toy figure, showing my new design.

What I claim as new, and desire to secure by Letters Patent, is—

The ornamental design for a toy figure, as shown.

LUDWIG RUCHSTEIN.
